FOOT-OPERATED CLUTCH MECHANISM FOR
PHYSICIAN'S EXAMINATION TABLESSam S. Spielberg, New York, N. Y., assignor to
Brooklyn Hospital Equipment Co. Inc., Johns-
town, Pa., a corporation of Pennsylvania

Application May 16, 1950, Serial No. 162,266

3 Claims. (Cl. 311—7)

1

The present invention has particular reference to physicians' examining tables, and more particularly to the type in which the top or supporting means for the patient is provided with an upper pivoted section by means of which the body of the patient can be inclined at any desired angle required for examination.

In tables of this character as constructed at the present time, means is provided for supporting the upper pivotal section of the table at various angles, such means including a clutch and a hand-operated lever for causing release of the clutch when it is desired to raise or lower the upper or head section of the table. During such raising or lowering movement the clutch must be disengaged and the upper section of the table and the portion of the body of the patient resting against the same must be supported and this support of the patient and pivotal portion of the table requires the use of both hands of the doctor, leaving no hand free to hold the clutch-release lever depressed. Hence, tables constructed as above described, usually require the services of both a doctor and nurse when raising or lowering of the upper section of the table is attempted, while the patient is resting against the same.

It is therefore an object of the present invention to provide means by which the pivotal upper section of the table is maintained at any desired angle, which means shall be foot-operated or controlled by the operation of a foot pedal, thus leaving the hands of the operator free to regulate the raising, descent of, or positioning of the pivotal upper part of the table.

More particularly, the invention contemplates the provision of a table top or body support having an upper pivoted section adjustable to any desired angular position and maintained in such position by means of a clutch device normally held in engaged position, said clutch device being capable of being released when desired by the pressure of a foot pedal, thus leaving the hands of the operator free to position the pivotal part of the table top at the desired angle.

With these and other objects to be herein-after set forth in view, I have devised the particular arrangement of parts to be described and more particularly pointed out in the claims appended hereto.

In the accompanying drawing, wherein an illustrative embodiment of the invention is disclosed, Fig. 1 is a view of the rear end of a physicians' examining table, constructed in accord-

2

ance with the invention, and with parts broken away to disclose construction; Fig. 2 is a side elevation of the table, with parts thereof broken away, and Fig. 3 is a detail view showing the clutch device for holding the pivotal portion of the table top or rest in various inclined positions.

Referring to the drawing, I generally indicates the table which may be of any of the known forms, and preferably, but not necessarily, made in whole or in part of metal. The table may be of cabinet form and is provided with the conventional padded rest or top on which the patient reclines, said top consisting of a lower or foot section 3, pivotally connected at 4 to the backrest 5, which is in turn, pivotally connected at 6 to the headrest 7. The backrest 5 and headrest 7 are herein referred to as the "upper pivotal section" since they are both raised and lowered to selected inclinations to position the upper part of the body of the patient at any desired angle for best examination. In Figs. 1 and 2, this pivotal upper section is shown in one of the inclined positions which it may assume. The lower portion 3 is also manually pivotal to various angles but this part of the table forms no part of the present invention.

Provided on the under side of the backrest 5 is a U-shaped bracket 8 receiving a pivot pin 9 on which is pivoted the upper end of a guide rod 10 extending downwardly and entering into the interior of the body of the cabinet through an aperture 30 provided therein. Said rod 10 is adapted to be engaged by a clutch device, operating with a wedging action on the rod 10, and which consists of a plate 11. Said plate 11 is formed with an opening or hole 12 through which the rod 10 freely passes as long as the plate 11 is maintained horizontally or nearly so. When the plate 11 is maintained in an inclined position, or substantially as shown in Figs. 2 and 3, the edges of the hole or aperture 12 will frictionally engage the rod 10 with a wedging action and thus maintain the rod 10 and the backrest 5 and attached headrest 7, against movement.

The clutch plate 11 is pivoted at one end on a pivot pin 14 supported in a bracket 15 mounted in the cabinet body 1. Adjacent to its free end, the plate 11 is formed with a laterally-extending lug 13 apertured to receive the upper end of a lifter rod 16. Said rod 16 has its upper end provided with either a head or a washer, and cotter pin 31 above the lug 13, and below the lug the rod 16 is provided with a stop or abutment 17

operative against the under side of the lug 13 to lift the lug and the plate 11 of which it forms a part, when the rod 16 is raised as will be explained.

The lower end of the rod 16 is pivotally connected at 18 to the rear end of a foot pedal 19 pivotally mounted at 27 in a bracket 29 at the lower part of the table cabinet. A spring 24 has one end attached to the lug 13 and has its other end attached to a bracket 22 attached to the rear wall 32 of the table. A second coil spring, indicated at 23, has one end attached at 26 to the lifter rod 16 and has its other end attached at 24 to the part 25 of the table.

From the foregoing, the operation of the improved table will be readily understood. In its normal position, the clutch plate 11 grippingly engages the rod 10 and thus maintains the upper pivotal section of the top or rest of the table in any position, horizontal or inclined, in which the same may be placed by the operator. The normal position of the clutch plate 11 is inclined to grip the rod 10, said plate being maintained in such inclined and engaged position by the downward pull of the springs 21 and 23. When it is desired to shift the position or angle of the upper pivotal section 5 and 7 of the table top, the foot pedal 19 is depressed by the foot of the operator, and this will cause the lifter rod 16 to be raised. The member 17 on said rod 16, engaging beneath the lug 13 will raise the plate 11 toward horizontal position and to an extent necessary to permit the guide rod 10 to slide through the hole or opening 12, thus permitting the upper pivotal section of the table top to be inclined as desired. The hands of the operator can be used to support and raise or lower the upper section 5 and 7 of the table while the patient is resting against the same, and while the foot is maintained on the pedal 19 until the desired inclination of the table top is attained. On release of the pressure of the foot on the pedal, the springs 21 and 23, exerting a downward pull on the lug 13 and lifter rod 16 respectively, will cause a downward swing of the clutch plate 11 to cause the plate to assume its engaged or gripping position and hold the rod 10 against any longitudinal movement and thus support the table top in any selected position of inclination.

It will thus be apparent from the foregoing that I have provided a table which can be readily operated smoothly and easily by one person, since the pivotal part of the table and the patient resting against the same can be supported by both hands of the operator while the clutching device is freed by foot operation. The result is that all shocks and jars to the patient are avoided while the table is being adjusted.

While I have shown one embodiment of the invention, it is obvious that the same is not to be restricted thereto, but is broad enough to cover all structures coming within the scope of the annexed claims.

I claim:

1. In a physicians' examining table, a cabinet table including a top having a pivoted upper section, a pedal pivotally mounted at the lower portion of the cabinet, a rod extending from said pedal, a pivotally mounted plate connected to the rod and caused to be pivotally moved toward the horizontal position by depression of the pedal, said plate being provided with an aperture, a guide rod attached to the pivotal upper section of the top, said guide rod extending through the

aperture in the plate and normally gripped by portions of the plate about the aperture and held against movement through said aperture, said plate being freed from engagement with the rod upon depression of the pedal, whereby the pivoted upper section of the table top may be moved to any desired angular position by the hands of an operator while foot pressure is maintained upon the pedal.

10. 2. In a physicians' examining table, a cabinet, a top mounted on the same, said top having a pivoted upper section, a rod pivoted at one end to the under side of the pivoted section and extending downwardly therefrom and into the cabinet, a pivoted clutch plate mounted in the cabinet and having an opening through which the rod extends, means for normally holding said clutch plate in an angular position to cause the same to grip the rod and hold the rod against sliding movement through the opening in said plate, a pivoted foot pedal located at the bottom of the cabinet, and a lifter rod having one end pivotally attached to the pedal and its other end in engagement with the clutch plate to cause 20 lifting movement of said clutch plate and clutching disengagement from the rod when the foot pedal is depressed, whereby the pivoted upper section of the table top may be moved to any desired angular position by the hands of an operator while foot pressure is maintained upon the pedal.

3. In a physicians' examining table, a table top and means for supporting the same, said top having a pivoted end section, a guide rod having one of its ends pivotally attached to the under side of the pivoted end section of the table top, a clutch member in the form of an apertured, pivoted plate hinged at one end below the top and having the guide rod extending through its aperture, spring means exerting a downward pull on the plate to normally hold it at an angle and cause it to grippingly engage the rod, said plate being provided with a lateral extension disposed at an angle to the plane of the plate, a push-rod attached at one end to the lateral extension, and a pedal pivoted below the table top and pivotally connected to the lower end of the push-rod to cause said push-rod to swing the plate toward horizontal when said pedal is depressed to thereby free the rod and permit movement of the pivoted end section of the table top by the hands of an operator.
